DRESS SHIRT

Sidney A. Avery, Paterson, N. J.

Application November 17, 1947, Serial No. 786,420

4 Claims. (Cl. 2—118)

1

This invention relates to an improved dress shirt of the type having a central opening and pleated bosom portions on both sides thereof, and to the method of making such shirt.

The invention has among its objects the provision of an improved dress shirt of the type indicated wherein preformed pleated bosoms are affixed to the respective bosom portions of a full shirt body, whereby the shirt is easily made to size, fits the wearer accurately and feels like the ordinary business shirt when being worn.

This and further objects of the invention will be more readily apparent in the following description of preferred embodiments of the shirt and of the method of making it.

Dress shirts with central openings and pleated bosom parts have been conventionally made by use of a shirt body having cut-out portions in the bosom parts, the cut-outs being only slightly smaller than the pleated bosom parts. The pleated bosom parts have then been applied to such body, and each has been attached thereto by sewing along the edge of the cut-out portion of the body, and the edge of its respective bosom part. Such operation is exacting and time-consuming, and must be performed very carefully to produce a shirt having a desired accuracy of fit and a pleasing appearance. The shirt of the present invention is made by employing a full shirt body; the pleated bosom parts being superimposed on the respective bosom parts of the body and permanently attached thereto by stitchings including one at the bottom edge of each of the pleated bosom parts and one along the edge of each remote from the central shirt opening. The shirt may thereupon be finished, if desired, in substantially the same manner as is employed to finish the ordinary business shirt having bosom parts of single thickness, which results in the pleated bosom parts being additionally stitched to the shirt body at the edge of the central opening and at the neckband. A dress shirt so made will thus fit accurately, if the full body thereof is made accurately, and the shirt is made by a method in which many of the operations are essentially similar to the usual ones in the shirt making industry; thus specially trained operators are not essential in making the shirt of the invention.

Preferred embodiments of the shirts of the invention, which are illustrative only, are shown in the accompanying drawings forming a part of the specification, in which:

Figure 1 is a view in front elevation of the bosom portion of a completely centrally divided

2

dress shirt made in accordance with a first embodiment of the invention;

Figure 2 is a view in front elevation of the right hand bosom portion of such shirt during an intermediate stage of its manufacture;

Figure 3 is a view in front elevation of the right hand bosom portion of the shirt at a later stage in its manufacture;

Figure 4 is a view in front elevation of the left hand bosom portion of the shirt in one stage of its manufacture;

Figure 5 is a view in cross-section through the shirt taken on the line V—V in Figure 1;

Figure 6 is a view in front elevation of the 15 bosom portion of a second embodiment of the shirt of the invention; and

Figure 7 is a view in cross-section through such shirt, the section being taken along the lines VII—VII in Figure 6.

20 As above indicated, one embodiment of the shirt is shown in Figures 1 to 5, inclusive, and the second in Figures 6 and 7. In the first embodiment, the right hand portion of the shirt body adjacent the central opening, hereafter termed the 25 body bosom portion, is designated 2. The corresponding portion of the shirt body at the left is denoted 4. Superimposed on such body bosom portions, respectively, are the right hand pleated bosom part 6, and the left hand pleated bosom part 8, both of which are made as separate, pre-formed, elements which are superimposed on the body bosom portions, and are permanently attached thereto by a method of which one embodiment will now be described in connection with the 30 forming of the right hand bosom portion of the shirt.

The preformed pleated bosom part 6, in which the pleats are fastened together by longitudinal stitchings 10, is placed upon the body bosom part 2 with its normally outwardly facing surface confronting the body portion and with the edge 11 thereof, which eventually becomes its lower edge, uppermost, as shown in Figure 2. Such position, for the sake of convenience, I term an "upper 45 face-down and bottom-edge-uppermost" position. A transverse stitch is then taken at 12 to attach the edge 11 of the pleated bosom to the body. Thereupon the pleated bosom is folded upwardly so that it assumes the position shown in Figure 3, the line of fold 14 coinciding with the line of stitching 12. The pleated bosom part 6 is then further attached to the body bosom part 2 by a line of vertical stitching 16 along the edge of the 50 pleated bosom part remote from the central opening of the shirt. Preferably stitching 16 is so

positioned as to lie under the last pleat of the part 6.

In the embodiment of the shirt shown, the edge 22 of the pleated bosom portion adjacent the central opening of the shirt and the edge 20 of the shirt body bosom part adjacent such opening are superimposed in coincident relationship. The portion of the shirt shown in Figure 3 is then finished by generally conventional shirt finishing operations which involve the folding of the edge of the shirt body upwardly. In this instance, however, because of the presence at such edge of the shirt of both the edge of the pleated bosom part and the edge of the body bosom part, there results the double fold 26 at the edge of the shirt adjacent the opening. A center piece 28 is then affixed to such edge of the shirt as by means of the two parallel stitchings 30 and 32. Preferably the center piece extends somewhat over the inner edge of the first pleat 24, as shown in Figure 5, which allows stitching 32 to penetrate the center piece, the first pleat, and the body 2 in that order, thus producing a symmetrical, strong, construction. The other stitching 30 extends through the center piece, the inwardly folded edge of the body, the folded edge and the unfolded edge of the pleated bosom part, and the unfolded body bosom part 2 of the shirt, in that order, as shown in Figure 5.

The left hand pleated bosom part 8 is attached at its bottom edge 34 and at its edge 35 remote from the central opening of the shirt in the same manner as the right hand pleated bosom part above described. In this case, however, the edge 38 of the pleated bosom part adjacent the central opening of the shirt is spaced somewhat inwardly from the edge 40 of the body bosom part 4, leaving a zone of material uncovered at 44. After attachment of the pleated bosom at its bottom and at its side edge 35, the edge of the bosom portion of the shirt adjacent the central opening is finished by folding over portion 44 of the body 4, as shown in Figure 5, and by stitching such parts together by the longitudinally extending stitching 46. As is evident from Figure 1, buttons 48 are attached to the left hand edge of the shirt body and button holes 50 are provided through the center piece and the body on the right hand portion.

It is to be understood that a shirt constructed as described may be provided with either a conventional attached collar including a neckband or with a neckband for a detachable collar; the latter is indicated at 92 in Figure 1. Such collar or neckband is affixed to the shirt in a conventional manner as by being superimposed thereon and being permanently attached thereto as by stitching 94 which extends through the folded neckband material, the pleated bosom part, the body of the shirt, and further folds of the neckband material, in that order.

In the second embodiment of the shirt of the invention shown, the material from which the pleated bosom portions are formed is appreciably thicker than that from which the body of the shirt is made. In this embodiment the right and left hand bosom parts of the shirt body are designated 2' and 4', respectively, corresponding pleated bosom parts being designated 52 and 54, respectively. The pleated bosom parts are applied to the body bosom parts at the bottom and side edges remote from the central opening of the shirt in the same manner as in the first embodiment described. The line of fold at the bottom of the right hand pleated bosom part coincident

with the bottom stitching is designated 56, and the vertical stitching at the edge remote from the opening 58.

In this embodiment, as shown more clearly in Figure 7, the right hand edge of the shirt at the opening is formed by placing the pleated bosom portion 52 some distance from the edge of the body portion, such body portion being folded at 64 up and around the unfolded edge 62 of the pleated bosom part 52. Such folded portion is denoted 66. A center piece 68 is then affixed to such edge by longitudinal stitchings 70 and 72. In the embodiment shown in Figure 6, the center piece slightly overlaps the first pleat 60 of the part 52 at its inner edge. Button holes 74 are provided through the center piece 68, through the part 62 of the pleated bosom part, and through body 2'.

The left hand edge of the shirt at the opening, in this embodiment, is finished in the manner clearly apparent at the left part of Figure 7. The pleated bosom part 54 is placed upon the body bosom part 4' so that the portion 78 of the former, which is of single thickness, has its edge 82 substantially coincident with the edge 80 of the body bosom portion. The two thicknesses of material are first folded close to the edge to form a fold 83, and are then folded at a location remote from the edge to form a second fold 84, as shown. The folded portions of the layers are retained in the described folded positions by means of the longitudinal stitching 86. Such stitching may be located as shown, so that it extends through four layers of material, or it may, if desired, be located at a position somewhat to the right of that shown so that it pierces all six layers of the material. The left hand edge of the shirt body at the opening, thus finished, is then provided with buttons 90 as shown.

Whereas I have described and illustrated preferred embodiments of the dress shirt of my invention, it is to be understood that such shirts may, within the scope of the invention, be varied somewhat as to details.

I claim as new the following:

1. A dress shirt having a full body with a central front opening to provide two bosom parts, each such bosom part of the body having a separate preformed pleated bosom part superimposed thereon and permanently attached thereto, each such pleated bosom part being attached to its respective body bosom part by stitching through an up and inturned edge of the lower edge of the pleated bosom part and the body bosom part, stitching at the side edge of the pleated bosom part remote from the front opening of the shirt, and an interfolding of the pleated bosom and body bosom parts and stitching through the pleated bosom and body bosom parts at said front opening.

2. A dress shirt having a full body with a central front opening to provide two bosom parts, each such bosom part of the body having a separate preformed pleated bosom part superimposed thereon and permanently attached thereto, each such pleated bosom part being attached to its respective body bosom part by stitching along and through an up and inturned edge of the lower edge of the pleated bosom part and the body bosom part, stitching along the side edge of the pleated bosom part remote from the front opening of the shirt, and an interfolding of the pleated bosom and body bosom parts and stitching therethrough and therewith at the side edge 75 of the pleated bosom and body bosom parts at said

front opening, at least one of such side edges of the shirt at the front opening having the side edges of the body bosom and the pleated bosom parts folded together, inwardly of the shirt.

3. A dress shirt having a full body with a central front opening to provide two bosom parts, each such bosom part of the body having a separate preformed pleated bosom part superimposed thereon and permanently attached thereto, each such pleated bosom part being attached to its respective body bosom part by stitching along and through an up and inturned edge of the lower edge of the pleated bosom part and the body bosom part, stitching along the side edge of the pleated bosom part remote from the front opening of the shirt, and an interfolding of the pleated bosom and body bosom parts and stitching therethrough and therealong at the side edge of the pleated bosom and body bosom parts at said front opening, at least one of such side edges of the shirt at the front opening having the side edges of the body bosom and the pleated bosom parts folded up together, one of such last named side edges of the shirt being provided with a center piece overlying the folded up side edges of the body bosom and the pleated bosom parts and secured thereto by stitching.

4. A dress shirt having a full body with a completely divided central front to provide a front opening and two bosom parts, each such bosom

20

30

part of the body having a separate preformed pleated bosom part superimposed thereon and permanently attached thereto, each such pleated bosom part being attached to its respective body bosom part by stitching through and along an up and inturned edge of the lower edge of the pleated bosom part and the body bosom part, stitching at the side edge of the pleated bosom part remote from the front opening of the shirt, 5 an interfolding of the pleated bosom and body bosom parts and stitching therethrough at the side edge of the pleated bosom and body bosom parts at said front opening, and by a neckband 10 at the top of the shirt which is attached to the shirt by stitching through the neckband and the body bosom part and the pleated bosom part of the shirt.
